FLOCKED TEXTILE FABRIC

Natalie Leavy, Clifton, N.J., assignor to Decorative Fabrics Company Incorporated, Pawtucket, R.I., a corporation of Rhode Island

Filed Dec. 28, 1960, Ser. No. 63,377

Term of patent 14 years

(Cl. D92—1)

The figure is a plan view of a flocked textile fabric, showing my new design with a portion of the design being broken away for convenience of illustration.

The design repeats horizontally and vertically as shown, the broken away portion consisting of floral sprays arranged as indicated, said sprays comprising in all ten rows.

I claim:

The ornamental design for a flocked textile fabric, as shown and described.
